UNITED STATES PATENT OFFICE.

WILLIAM H. PERCIVAL, OF BAYSWATER, GREAT BRITAIN.

STRINGED MUSICAL INSTRUMENT.

SPECIFICATION forming part of Letters Patent No. 225,997, dated March 30, 1880.

Application filed December 12, 1879.

To all whom it may concern:

Be it known that I, WILLIAM HENRY PERCIVAL, of Bayswater, in the county of Middlesex, Kingdom of Great Britain and Ireland, have invented new and useful Improvements in Stringed Musical Instruments Played by Bows or Plectra, of which the following is a specification.

My invention relates to stringed musical instruments played by bows or plectra, and is designed to give increased body or fullness to the tone of such instruments and to facilitate the playing thereof.

Referring to the accompanying sheet of drawings, Figure 1 is a plan of part of an instrument embodying my invention. Fig. 2 is a perspective view, partly in section, to a larger scale; and Fig. 3 is a plan, half in section, with the key-board removed.

My invention consists, first, in the application of a loose sounding-board, *a*, interposed between the finger or fret board *b* (or belly or top) and the back or bottom *c* of the hollow body of the instrument. This sounding-board is secured to the ends of the hollow body at *c* and *f*; but between these two parts the sound-board *a* is partly bowed or bent downward, (see Fig. 2,) and is made narrower than the internal width of the hollow body, so as to leave small spaces *g* between the edges of the sound-board *a* and the sides *h* of the hollow body, as shown in Fig. 3. By this construction, arrangement, and application of the sound-board *a* it is left free to vibrate without touching any part of the hollow body of the instrument except at the ends. The instrument I have shown is an improved one of the zithern class, and the top of the instrument extends only to the point marked *i*, leaving the rest of the hollow body (from *i* to *f*) open at the top, except so far as the loose sound-board itself forms a cover. *k* are the frets or bars of wire to indicate where the fingers are to be placed for playing certain notes; *l l*, the wires or strings; *m m*, the hitch-pins; *n n*, the wrest or tuning pins, and *o* is the bridge.

My invention consists, secondly, in combin-

ing with the loose sounding-board and fret-board above described a key-board and keys 50 or studs, which may be arranged as shown in Figs. 1 and 2, or as shown in Fig. 4.

Referring to Fig. 2, *k* are the studs, arranged one over each fret, and having spiral springs *k*² in the hollow key board or box *k*³, 55 for returning the studs or keys to their normal positions.

Although my improved instrument, as illustrated, is of oblong rectangular form in plan, and has only two wires or strings, it 60 will be evident my invention may be applied to other forms of instrument of the same class, and that my loose sounding-board may be used in the zithern or violin, bass-viol, violoncello, and all instruments of this character, and 65 that instruments such as I have shown may be more or less varied in shape, and be provided with more wires or strings, so long as a loose sounding-board, *a*, be applied thereto, as above set forth.

What I claim is—

1. As an improvement in a stringed musical instrument adapted to be played by a bow or plectrum, a loose sounding-board curved downward and interposed between the finger 75 or fret board (or belly or top) and the back or bottom of the hollow body of the instrument, said loose sounding-board being narrower than the transverse width of the body, to form spaces *g*, and secured only at the ends, substantially as described.

2. In a stringed musical instrument adapted to be played by a bow or plectrum, the combination of a loose sounding-board, a fret-board, and a key-board with studs or keys provided 85 with springs for returning same to their normal positions, said studs or keys being arranged to press the strings or wires against the frets, substantially as described.

WILLIAM HENRY PERCIVAL.
